UNITED STATES PATENT OFFICE.

HORACE B. WRIGHT AND HAROLD FROST HEWETSON, OF YOUNGSTOWN, OHIO, AS-SIGNORS TO THE GENERAL FIREPROOFING COMPANY, OF YOUNGSTOWN, OHIO, A CORPORATION OF OHIO.

METALLIC CLIP FOR ATTACHING METAL LATH.

Application filed October 6, 1921. Serial No. 505,863.

To all whom it may concern:

Be it known that we, HORACE B. WRIGHT and HAROLD FROST HEWETSON, citizens of the United States, residing at Youngstown, in the county of Mahoning and State of Ohio, have invented certain new and useful Improvements in Metallic Clips for Attaching Metal Lath, of which the following is a specification.

10 This invention relates to devices of the clip type for attaching or securing expanded metal lath to metal lumber.

To that end the invention contemplates a simple and practical form of clip which 15 may be readily produced economically, and in commercial quantities, for attaching expanded metal lathing or the like to the flanges of metal lumber securely and expeditiously.

20 A further and more specific object of the invention is to provide a clip having a lath supporting body of maximum resiliency, and also adapted to engage with the support in such a manner as to effect a secure anchorage for the metal lathing.

With the above and other objects in view which will more readily appear as the nature 25 of the invention is better understood, the same consists in the novel construction, combination and arrangement of parts, herein-after more fully described, illustrated and claimed.

A preferred and practical embodiment of the invention is shown in the accompanying drawings, in which:

35 Figure 1 is a bottom plan view of a structural member and lathing united by a clip constituting the present invention.

Figure 2 is a vertical sectional view taken 40 on the line 2—2 of Figure 1.

Figure 3 is a vertical sectional view taken on the line 3—3 of Figure 1.

Figure 4 is a detail perspective view of the improved clip.

45 Similar reference numerals designate corresponding parts throughout the several figures of the drawings.

In carrying the invention into effect, it is proposed to provide an attaching clip 50 made of a single piece of spring wire of suitable gauge. To that end a suitable length of wire may be bent to form a relatively resilient supporting body adapted to engage with the lath and having hooked arm

portions at the ends thereof to engage with the studding or other structural member.

Accordingly, as will be observed from the drawings the present clip essentially consists of the body 1 having the attaching arms 2 at the opposite ends thereof, and the said body being deformed or bent inwardly to provide the medial head portion 3, and also bent laterally to provide the relatively divergently related body sections 4, which join with the angularly disposed attaching arms 2. The ends of these arms are formed with the hooks 5 for engaging with the metal lumber, and are both offset laterally on the same side of the arms to permit of the same engaging over the flange F of the channel bar C, as shown in Figure 2 for example.

The formation of the clip above described provides a relatively resilient body which is deformed laterally and inwardly and lies in a plane oblique to the arms 2, the hooks 5 of which are bent or formed at the same side of the arms as the body portion 1. By offsetting the body 1 laterally and at the same time upwardly at its medial portion to provide a pressure head for engaging with the lath L, for instance, the desired resiliency is obtained without spreading the arms 2 as might be the case if the body 1 were only bowed or bent inwardly when the clip was applied. That is to say, the lateral offsetting of the body has the effect of providing a resilient portion which flexes more or less in the zone of the angle or elbow 4 formed between the vertical attaching arms and the resilient sections 4 of the body. The resilience is largely due to torsional stresses instead of bending stresses.

While metal clips have been heretofore used for attaching expanded metal lathing to metal lumber, such clips have generally had the hooks for engaging with the metal lumber bent inwardly in a plane parallel to the body of the clip. However, the present invention departs from that practice by forming the hooks 5 at right angles to the general disposition of the body 1, and also proposes to bend the body laterally so as to have the same lie in a horizontal plane also at an angle to the arms, thereby to provide the hooks and body extending substantially horizontal to the same side of the vertical arms of the clip. This arrangement permits of the clip occupying a position paral-

lel with the flange of the beam instead of transversely thereto, as in the case of clips which have the hooks bent inwardly and substantially in the plane of the body of the clip.

In installing the clip for use, it is only necessary to insert the arms 2 having the hooks 5 thereon through the meshes of the lath and place one of the hooks over the 10 flange of the beam with the compression head 3 of the body engaging with the lath. Then, the other attaching arm 2 may be forced into position, whereby the hook 5 thereof will also engage with the flange of the beam, either by a hammer blow or any 15 other suitable means for reliably and expeditiously driving the clip to its final position.

Without further description it is thought 20 that the features and advantages of the present invention will be readily apparent to those skilled in the art, and it will of course be understood that changes in the form, proportion and other minor details 25 of construction may be resorted to without departing from the spirit of the invention or scope of the appended claims.

We claim:—

1. A wire clip of the class described including a clamping body having offset attaching arms at the ends thereof, supporting hooks formed on the arms and extending at right angles to the body, said body being bent laterally in the same direction 30 as the hooks, and also toward the same to provide a medial resilient rib-engaging head.

2. A clip of the class described formed by a single piece of wire bent to provide a 40 relatively horizontal body and angularly disposed attaching arms, laterally offset supporting hooks formed on the ends of the arms, and the said body of the clip being

bent at its medial portion laterally and toward the hooks to provide a yielding compression head located at one side of a plane intersecting both of the arms. 45

3. A clip of the class described formed by a single piece of wire bent to provide a relatively horizontal body and angularly disposed attaching arms, laterally offset supporting hooks formed on the ends of the arms, and the said body of the clip being bent at its medial portion laterally and toward the hooks to provide a resilient lath 50 engaging head at said medial portion and adapted to flex at a point substantially at the junction of the arms with the body. 55

4. A clip of the class described formed from a single piece of wire bent to provide a body adapted to be positioned parallel to the edge of the structural member with which it engages and having arms at the opposite ends thereof provided with offset hooks, and said body being bent laterally 60 and toward the hooks to form convergent resilient sections joining in a resilient head portion located substantially at right angles to the plane of the attaching arms. 65

5. A clip of the class described including 70 spaced arms provided with offset supporting hooks and connected by a body also bent to the same side of the arms as the hooks, and the said body being bent toward the hooks to provide a relatively constricted clamping jaw adapted to yield in the direction of the arms. 75

In testimony whereof we hereunto affix our signatures in the presence of two witnesses.

HORACE B. WRIGHT.
HAROLD FROST HEWETSON.
